ATTORNEYS

UNITED STATES PATENT OFFICE.

JOHN V. HUETHER, OF BROOKLYN, NEW YORK.

FOUNTAIN BRUSH.

Application filed July 5, 1922. Serial No. 572,843.

To all whom it may concern:

Be it known that I, JOHN V. HUETHER, a citizen of the United States, and a resident of the city of New York, borough of Brooklyn, in the county of Kings and State of New York, have invented a new and Improved Fountain Brush, of which the following is a full, clear, and exact description.

This invention has relation to combined 10 containers and applicators for semi-liquid or paste coating substances such as shoe or stove polishes or the like.

Some of the principal objects of the present invention reside in the provision of an 15 applicator such a brush or dauber which includes means for the accommodation of a supply of polish or other substance; means for feeding, as needed, the said substance onto the bristles thereof; means for closing 20 the feed to prevent waste or drying out of the substance; and means for facilitating the replenishing of the supply when exhausted.

As a further object the invention contemplates in combination with an applicator of 25 the character described an improved package for the polish or substance which serves as a reservoir when associated with the applicator and cooperates with the feeding means thereof to discharge the contents 30 therefrom, said package being adapted to be removed and discarded when empty and replaced by a similar package purchasable for the purpose.

The invention furthermore contemplates 35 in a device of the character described a new article of manufacture which is simple in its construction, inexpensive to produce, and which is thoroughly reliable and highly efficient in its purpose.

With the above recited and other objects 40 in view, the invention resides in the novel construction set forth in the following specification, particularly pointed out in the appended claims and illustrated in the accompanying drawing, it being understood 45 that the right is reserved to embodiments other than those actually illustrated herein to the full extent indicated by the general meaning of the terms in which the claims 50 are expressed.

In the drawing—

Figure 1 is a side elevation of an applicator constructed in accordance with the invention, the head thereof being shown in 55 section.

Fig. 2 is a plan view with parts broken

away to disclose the underlying structure.

Fig. 3 is a sectional view through the package constituting the reservoir for the 60 applicator.

Referring to the drawing by characters of reference, the applicator which is here illustrated as a brush or dauber comprises a handle 10 and a brush head 11 which constitutes a support for the bristles 12. The 65 head 11 on the opposite side from the bristles is recessed as at 13 and is provided with a concentric threaded aperture 14 which establishes communication between the recess 13 and the opposite side of the head 70 from which the bristles are supported. The open side of the head 11 is exteriorly threaded at 15 to receive and accommodate a removable cover 16 provided with a central 75 interiorly threaded bearing boss 17 in which a manipulating screw 18 is mounted. The manipulating screw is provided at its outer end with a winged head 19 and at its inner end with an enlarged bearing disk 20.

The package which is adapted to be associated with the brush or dauber to constitute a reservoir therefor consists of a container 21 of a configuration and size to snugly fit within the recess 13 with a portion thereof projecting out of the recess and 85 embraced by the removable cover 16 for the brush head. The body of the container 21 is provided at one end with a closed end wall 22 having a combined centrally disposed filling and discharge nozzle 90 23 which is exteriorly threaded as at 24 to accommodate a closure cap 25. The opposite end of the body of the container is open and receives an axially movable wall or follower 26 which snugly conforms to and fits 95 the interior configuration of the body of the container. After the wall or follower 26 is inserted within the container, the open end is turned inwardly to provide an annular bead 27 which prevents the removal of the 100 wall or follower 26 and constitutes a seat therefor when the container is filled with a substance 28 such as a polish in semi-liquid or paste form. Preferably the filling of the container is through the nozzle 23.

In practice after the removable cover 16 of the brush head is disassociated therefrom, and the closure cap 25 is removed from the nozzle 24, the container 21 is inserted in the recess 13 in the brush head with the exteriorly threaded nozzle 23 engaged in the 110 threaded opening 14.

The manipulating screw 18 is retracted to the full extent and the cover 16 is replaced on the brush head. The applicator is then ready for use. By manipulating the screw 18 through the winged head 19 the bearing disk 20 at the inner end of the screw 18 is brought into contact with the axially movable wall or follower 26 of the container to advance the same toward the discharge nozzle 23 for effecting the discharge of the contents of the container therefrom onto the bristles 12. When not in active use it has been found desirable to close the feeding or discharge nozzle 23 in order to prevent waste and an access of air thereto. For this reason the slide valve 29 is provided which consists of a flat strip of material having a central slot 30 through which the headed elements 31 are passed and anchored into the brush head. The outer end of the strip is up-turned to provide a manipulating handle 32, while the inner end thereof, when the handle 32 is adjacent the side of the head 11, serves to cover the discharge nozzle and snugly impinge thereagainst to prevent waste of the contents or the access of air therethrough.

From the foregoing it will be seen that an applicator in the nature of a dauber or brush for shoe or stove polish has been provided together with a container which cooperates therewith to constitute a reservoir for the polish, said container serving as a package for the polish which is sold upon the market as a refill for the applicator. This arrangement prevents soiling of the hands of the user and effects an economy in the use of the polish or other substance.

I claim:

1. In combination, a container having one end wall provided with an outlet and an axially movable end wall constituting a follower for expressing the contents thereof through the outlet, and an applicator comprising a brush including a head provided with a recess in the opposite side of which the bristles are disposed, said brush head having an opening establishing communication between the recessed side and the bristled side, said recess adapted to receive the container and said opening adapted to register with the outlet, and means carried by the applicator adapted to coat with the movable end wall of the container for expressing the contents through the outlet.

2. In combination, a container having one end wall provided with an exteriorly threaded outlet nozzle and an axially movable end wall constituting a follower for expressing the contents thereof through the outlet nozzle, an applicator comprising a brush including a head provided with a recess in the opposite side of which the bristles are disposed, said brush head having a threaded opening establishing communication be-

tween the recessed side and the bristled side, said recess adapted to receive the container and said threaded opening the outlet nozzle, means carried by the applicator adapted to coat with the movable end wall of the container for expressing the contents through the outlet nozzle, and means on the applicator respectively shiftable to positions for covering and uncovering the outlet nozzle.

3. In combination, a container having one end wall provided with an exteriorly threaded outlet nozzle and an axially movable end wall constituting a follower for expressing the contents thereof through the outlet nozzle, an applicator comprising a brush including a head provided with a recess in the opposite side of which the bristles are disposed, said brush head having a threaded opening establishing communication between the recessed side and the bristled side, said recess adapted to receive the container and said threaded opening the outlet nozzle, a cover detachably associated with the brush head, and a manipulating screw extending therethrough adapted to coat with the movable end wall of the container for advancing the same toward the outlet nozzle for discharging the contents through said outlet nozzle.

4. In combination, an applicator including a head, bristles supported from one side thereof and a recess formed in the opposite side, said head having a passage therethrough establishing communication between the recess and the bristled side thereof, a container having one end wall provided with an outlet nozzle and an axially movable opposite end wall constituting a follower, said container constituting a package for the substance to be applied by means of the applicator and adapted to be arranged in the recessed head with the nozzle extending through the passage thereof whereby to afford a reservoir for the applicator, and means carried by the applicator adapted to coat with the movable end wall for expressing the contents of the container through the outlet and onto the bristles.

5. An applicator brush including a bristle supporting head having a recess in the opposite side from which the bristles are supported, said head having a passage between the recessed and bristled sides thereof, a closure for the recessed side, a manipulating screw extending through the closure in combination with a container having an end wall provided with an outlet nozzle, and an axially movable opposite end wall constituting a follower adapted to be advanced toward the other end wall for expressing the contents through the outlet nozzle, said container constituting a refill package for the applicator brush insertable within the recessed head with the nozzle protruding through the passage to provide a reservoir

- with the movable end wall of which the manipulating screw coacts to effect the discharge of the contents through the outlet nozzle and onto the bristles.
- 5 6. An applicator brush including a bristle supporting head having a recess in the opposite side from which the bristles are supported, said head having a passage between the recessed and bristled sides thereof, a
10 closure for the recessed side, a manipulating screw extending through the closure in combination with a container having an end wall provided with an outlet nozzle, and an axially movable opposite end wall constituting a follower adapted to be advanced
15 toward the other end wall for expressing the contents through the outlet nozzle, said container constituting a refill package for the applicator brush insertable within the recessed head with the nozzle protruding 20 through the passage to provide a reservoir with the movable end wall of which the manipulating screw coacts to effect the discharge of the contents through the outlet nozzle and onto the bristles, and a strip slidably mounted on the bristled side of the brush head constituting a closure respectively shiftable into covering and uncovering relation to the passage and nozzle.

JOHN V. HUETHER.
